UNITED STATES PATENT OFFICE.

ELROY A. CHASE, OF NORTHEFIELD, VERMONT.

SLUDGING WHEEL.

Application filed November 4, 1922. Serial No. 599,037.

- This invention relates to a wheel for use in polishing granite and similar material and particularly to a wheel for use in the intermediate or so-called sludging operation.
- 5 In my improved process of polishing granite, the finished surface is produced by three distinct or successive operations, namely coarse grinding, sludging or fining-up, and buffing.
- 10 My present invention relates to improved features of construction in a wheel of the ring type adapted to perform the intermediate fine grinding or sludging operation to great advantage.
- 15 It is my general object to provide a wheel in which vibration is reduced to a minimum and in which the action of the grinding material quickly produces a surface unusually well prepared for the final or buffing operation.

With this general object in view my invention relates specifically to certain details of construction and arrangements of parts which will be hereinafter described and 25 more particularly pointed out in the appended claims.

A preferred form of the invention is shown in the drawings, in which—

Fig. 1 is a partial plan view of my improved sludging wheel;

Fig. 2 is a sectional elevation taken substantially along the line 2—2 in Fig. 1, and

Fig. 3 is a partial plan view showing approved driving connections for the wheel.

35 Referring to the drawings, I have shown a wheel of the ring type, comprising a plurality of concentric metal rings 10 spaced apart and also spaced from the axis of the wheel, as clearly shown in Fig. 2. The rings 40 10 are connected by four or more radial arms 11, equally spaced about the periphery of the wheel and provided in sufficient numbers to firmly support the rings whenever any portion of the wheel passes beyond the 45 edge of the stone.

One of the rings 12 may be increased in thickness as shown in Fig. 2, to provide a circular rib 13 connecting the arms 11. A driving head 14 is provided with arms 15 50 which are preferably secured to the ring wheel by bolts or screws 16 at the points where the arms 11 intersect the rib 13. Intermediate wheel arms 17 may be provided, as indicated in Fig. 1, between the points 55 at which the arms 15 are attached.

The arms 15 are preferably of such cross-

section that a relatively sharp edge will be presented at the forward side of each arm when the wheel is in operation, the under face of each arm being downwardly and rearwardly inclined from the leading edge. This facilitates the feeding of abrasive material to the central opening 19 within the inner ring and avoids scattering and waste of the material.

65 An important feature of my invention relates to the provision of blocks 18 of cushion material between the driving arms 15 and the ring wheel. These blocks reduce vibration and thus contribute to the smooth 70 running of the wheel.

The driving head 14 is provided with notches or recesses 20 (Fig. 2) to receive the ends of a cross pin 21 secured by a universal connection 22 to the end of a driving shaft 75 23. Each notch 20 has an abrupt driving face on one side and a rearwardly inclined face on the opposite side, thus making it easy to insert the cross pin in the notches for driving the wheel or to release the pin from 80 the wheel when a change in wheel is desired.

Having thus described the construction of my improved sludging wheel, the method of operation and advantages thereof will now be indicated. This type of wheel is particularly designed for sludging or fining-up 85 relatively small blocks of stone and is consequently made in such sizes that the wheels can be readily changed for the different steps of the finishing operation. The wheel 90 being placed upon the block, the driving shaft 23 is lowered until the cross pin 21 engages the notches 20 to rotate the wheel. The abrasive material is preferably fed through the central opening 19 and a fine 95 stream of water is also commonly directed against the work at this point, the rate of flow being carefully controlled. It is found that the cushion blocks 18 largely eliminate 100 vibration of the wheel and that the increased stiffness of the wheel, due to the provision 105 of the equally spaced arms 11 and 17, also materially assists in preventing vibration. This reduction of vibration prevents the forming of rings on the work by irregular contact of the wheel therewith and also permits the wheel to run beyond the edges of the block of stone without forming scratches or rings at the point where the wheel returns to the stone.

110 Having thus described my invention and the advantages thereof, I do not wish to be

limited to the details herein disclosed otherwise than as set forth in the claims, but what I claim is:—

1. A sludging wheel comprising a plurality of concentric rings, radial arms connecting said rings, a circular rib integral with one of said rings and connected to said arms and substantially spaced outwardly from the inner ends of said arms and from the inner ring and said rib passing above and being secured to all of said arms, and driving means for said wheel including a driving ring connected to said circular rib at a plurality of points of intersection of said rib with said arms.
2. A sludging wheel comprising a plurality of concentric rings, a plurality of radial arms connecting said rings at equally spaced

points, a driving ring for said wheel, means to secure said ring to said arms, and separate cushion devices interposed between said head and said arms at each point of attachment thereof.

3. A sludging wheel comprising a plurality of concentric rings, radial arms connecting said rings at a plurality of points, a driving head, and means to connect said driving head to certain of said radial arms, said arms having their forwardly directed portions formed in relatively sharp edges to facilitate the feed of abrasive between said rings.

In testimony whereof I have hereunto affixed my signature.

ELROY A. CHASE.
